CYLINDER MOUNTING MEANS FOR ROTARY
PRINTING APPARATUS

William C. Huebner, New York, N. Y.

Application August 9, 1949, Serial No. 109,306

10 Claims. (Cl. 101—216)

1
This invention relates to a printing or coating press and, more particularly, to constructions thereof for facilitating removal therefrom of a printing or coating element such as printing, inking, or like cylinders or drums; this application being in part a division of my copending application S. N. 689,490 filed August 9, 1946, now Patent No. 2,557,381 dated June 19, 1951, and also including a modification of the divided subject matter.

My above-identified copending application discloses a universal press which is readily adapted for printing by different methods and/or in different colors. In such a press it is desirable that the printing elements such as the printing, inking, or like cylinders or drums be readily removable from the press to permit cleaning and also to facilitate replacing the cylinders with others having different surface characteristics when the mode of printing or the image or color to be printed is to be changed.

An object of this invention is the provision in a printing or coating press of an improved means for mounting an element or elements, such as printing, inking, or like cylinders or drums, whereby the elements or drums may be readily removed from the press for cleaning or for replacement by a different drum or element, the removal and replacement being effected without dismantling the press.

Another object of the invention is the provision of an improved means for mounting cylindrical elements in a printing or coating press wherein the said elements comprise cylindrical shells which are engaged and rotatably mounted in the press by end members having a sliding fit within the ends of said cylinders, at least one of said end members being axially movable with respect to the other end member to facilitate removal of said shell.

A further object of the invention is the provision of an improved means for mounting cylindrical elements in a printing or coating press wherein the said elements comprise cylindrical shells the ends of which are closed by disk-like members to form hollow drums, the said drums being rotatably mounted in the press by bearing members, at least one of which is axially movable to facilitate removal of the drum from the press.

A still further object of the invention is the provision of improved means for mounting a printing or coating element in a press as defined in the two preceding objects and wherein means are provided for facilitating alignment and support of said element during removal and placement thereof.

2
An additional object of the invention is the provision in a printing or coating press of an improved hollow element and improved rotatable mounting means therefor wherein the said element is adapted to have liquid supplied to the interior thereof for effecting a printing or coating operation and the element is adapted to be readily placed in and removed from the press by axial movement of at least one of the mounting means, characterized in that the said element and movable mounting means have cooperating valve means which are automatically opened to permit supply of liquid therethrough to the interior of the drum when the latter is in place in the press, the said valve means automatically closing when the drum is removed from the press.

The invention further resides in certain novel features of construction and combination and arrangements of parts, and further objects and advantages thereof will be apparent to those skilled in the art to which it pertains from the following description of the present preferred embodiment thereof, and certain modifications, described with respect to the accompanying drawings in which similar reference characters represent corresponding parts in the several views and in which:

Fig. 1 is a fragmentary transverse sectional view through a printing press provided with a cylindrical printing element constructed and mounted in accordance with this invention, this figure being identical with Fig. 9 of my aforementioned copending application S. N. 689,490 except that the reference characters have been changed;

Fig. 2 is a fragmentary elevational view as seen from a location corresponding with the line 2—2 of Fig. 1 showing a means for effecting correct circumferential positioning of the printing element, this figure being identical with Fig. 9b of my aforementioned copending application except that the reference characters have been changed;

Fig. 3 is a fragmentary transverse sectional view through a printing press provided with the present preferred embodiment of a cylindrical printing element incorporating the features of this invention;

Fig. 4 is a fragmentary view partly in end elevation and partly in section taken substantially on the line 4—4 of Fig. 3;

Fig. 5 is a fragmentary sectional view taken substantially on the line 5—5 of Fig. 4; and,

Figs. 6 and 7, taken together, comprise an enlarged fragmentary view of the lefthand portion of Fig. 1 principally in elevation but with parts broken away and others shown in section to illustrate the operation of the cylinder mounting and

valve means when the former is withdrawn from supporting relationship with the printing element to effect placement or removal of the element.

A printing press as disclosed in my aforementioned copending application S. N. 689,490 preferably comprises tiers of drums or cylinders for effecting a printing operation, which tiers are movable to and from each other by virtue of being supported and guided on a base member 10. For this purpose the base is provided with upstanding rails 11 and 12 on which the tiers are movably mounted by having the lower member 13 thereof provided with rollers 14 supported on channels or ways such as 15 and cooperating with the rails 11 and 12 for movement longitudinally therewith. The tiers are secured in a selected, predetermined position by suitable means such as a locating pin 16 which may pass through aligned holes in one of the rails and a portion of the member 13.

Supported upon the member 13 are one or more frame members or units 17 only one of which is shown in detail herein, these members being castings which extend transversely of the base and are each provided on the under side with keyways 18 and on its upper side with keys 19. The keyways 18 of the lowermost unit 17 interfit with the keys 20 of the supporting member 13 and the keys 19 at the top of unit 17 interfit with corresponding keyways in the next unit thereabove or with a cap member, not shown. The units 17 are ordinarily connected together and to the supporting member 13 by suitable securing means such as bolts 21 thereby constituting a rigid frame.

Supported within the frame member 17 is a printing element or drum, generally designated 22, which includes rotatable spaced apart flanged disks 23 and 24. The disk 23 is rotatably supported in an eccentric bushing 25 which is in turn mounted in an eccentric sleeve 26. The other disk 24 is likewise supported in an eccentric sleeve, as will presently appear, and therefore the axis of the element or drum 22 may be 45 adjusted in directions at right angles to its axis by rotation of the eccentric sleeves. The sleeve 26 may be locked in an adjusted position by means of a screw 26a which extends through a slot in the flange of the sleeve and is threaded into the frame 17. The sleeve 26 is provided with a key or pin 27 which extends into a keyway 28 in the bushing 25 so that the bushing together with the bearing portion of the disk 23 can have endwise movement relative to the sleeve 26. For this purpose, the bushing 25 is externally threaded and supports a gear nut 29 located between the flange of the sleeve 26 and a retainer plate 30 rigidly secured to the frame. A pinion 31 meshes with the teeth of the nut 29 and is fixed to a shaft 32 which is rotatably supported by the frame member 17 and by the plate 30, the outer end of shaft 32 having its outer end provided with a portion to which a removable operating handle or crank 33 may be attached. It will be apparent from the construction just described that, when the pinion 31 is rotated by the handle 33, the nut 29 will turn and thread upon the bushing 25 causing the latter to move axially inwardly or outwardly depending upon the direction of the rotation of the handle 33. Since the outer end of bearing portion of disk 23 has a plate 23a secured thereto with a portion of the bushing 25 received between this plate and an integral shoulder on the 75

bearing portion of the disk, the axial movement of bushing 25 carries the disk 23 therewith.

The disk 24 has a reduced diameter bearing portion thereon rotatably mounted in an eccentric bearing sleeve 34, this sleeve having a flange portion which is adjustably secured to the frame 17 by a screw or the like 35 to retain the circumferential adjustment of the sleeve and prevent axial displacement thereof. A sleeve 36 is fixed to a reduced diameter of the bearing portion of the disk 24, intermediate the latter and the eccentric bearing sleeve 34, and has a shoulder engaging the outer end of the bearing sleeve 34. This sleeve 36 has a gear 37 formed thereon, which will be referred to hereinafter, the outer face of which gear engages a boss on a gear cover or casing 38 to prevent endwise displacement.

Each of the disks 23, 24 has the inner face thereof secured to a supporting plate 39 and 40, respectively, which are preferably formed of insulating material, these plates being provided at their circumference with internal and external circular shoulders such as 41 and 42. The supporting plates 39 and 40 are adapted to support various types of hollow cylinders or cylindrical shells 44 with the opposite ends of the latter bearing upon the shoulders, such as 42, or upon spacing rings, such as 43, interposed between the said shoulders and the cylindrical shells 44, these cylindrical shells being clamped between the flanges of the disk members 23, 24 and of the plates 39 and 40 when spaced apart a predetermined distance.

The disk 23 is provided centrally with a recess facing towards the disk 24 and in which is mounted a bearing 45 adapted to support a stationary tube 46 which extends through central openings in the plates 39 and 40 with a substantial clearance. The tube 46 extends slightly into a central bore in the disk 24 and the end of the tube is detachably connected by interlocking relationship, such as by a tongue and groove connection, with a fixed tube 47. The tube 47 is stationarily mounted in the frame and extends through the bore of the bearing portion of the rotatable disk 24 with a clearance, the tube 47 extending into a supporting boss formed in the wall of the gear casing 38 and held stationarily with respect thereto by means of a screw 48 or the like.

Let it be assumed that the disks 23, 24 are positioned in cylinder supporting relationship, that a cylinder is mounted on the cylindrical shoulders of the plates 39, 40 or on the rings 43, and that the tube 46 is in position as shown in Fig. 1 and is connected to the tube 47. It will be apparent that rotation of the disk 24 by means of gear 37 will cause the entire drum, including the cylinder 44 and the disk 23, to rotate while the tubes 46, 47 remain stationary. Now assuming that it is desired to remove the cylinder 44, the operator applies the handle 33 to the outer end of the shaft 32 and rotates this shaft to cause the bushing 25 and the disk 23 to move axially outwardly, as previously explained, away from the disk 24 with the result that the circular shoulders on the plates 39, 40 are spaced apart a greater distance than the length of the cylinder 44, it being understood that the disk 23 can move outwardly until it contacts the wall of the unit 17. The outward movement of the disk 23 also causes disengagement of the left-hand end of the tube 46 from the bearing 45 so that both the cylinder and the tube 46 will be free for removal from the unit. This removal is effected by ax-

ially moving the cylinder 44 and tube 46 sufficiently to disengage them from plate 40 and tube 47, respectively, whereupon the cylinder is moved out of the frame at right angles to the normal axis of the drum or element.

When it is desired to insert a cylinder in the unit as for instance, another type of cylinder or one having different surface configurations, a cylinder 44 with the tube 46 therein is inserted into the unit with the righthand end of the cylinder, as viewed in Fig. 1, resting upon the shoulder of plate 40, or upon the ring 43, and with a rod passing through a central opening 49 in the disk 23 and engaging in a central recess 49a in the closed end of the tube 46 to hold the latter in properly aligned position with the tube 47 and with the bearing 45 to facilitate proper positioning of the tube. The opening 49a and the end of the tool engaging therein preferably have cooperating polygonal shapes to permit rotation of the tube 46 and thereby effect interlocking engagement of the tongue and groove joint of the tube with tube 47. The cylinder 44 is provided with a notch 50 (see Fig. 2) in its right-hand end thereof which is adapted to be aligned with and receive a key or projection 51 carried by the disk 24. This facilitates positioning the cylinder 44 circumferentially with respect to the driving mechanism therefor so that the images produced thereby will be properly correlated with those previously or subsequently produced by other cylinders of the press. With the cylinder and tubes thus positioned, the operator then turns the handle or crank 33 to cause the disk 23 to move inwardly towards the disk 24 until the cylinder 44 is tightly clamped on the circular shoulders of the plates 39, 40 or on the rings 43 and between the flanges thereof, the left-hand end of the tube 46 being positioned in the bearing 45 and the right-hand end of this tube interengaged with the left-hand portion of the tube 47.

An alternative way of mounting the cylinder in position is to remove the plates 39, 40 and assemble the cylinder 44 on the shoulders of the plates with or without the rings 43 interposed therebetween, depending upon the characteristics of the cylinder, and then insert the tube 46 through the central openings of the plates. This assembly can then be mounted at one end on the disk 24 while its other end is supported by a tool in the opening 49, with a polygonal end thereon engaging the correspondingly shaped socket 49a in the end of the tube 46. The tube 46 is thus centered and can be rotated to engage the tongue and groove connection between it and the tube 47 whereupon the disk 23 is moved into supporting relationship with its cooperating disk 24 by means of crank 33.

The gear 37 of each element is driven in a manner fully described in the aforementioned copending application S. N. 689,490. As disclosed therein, the press is provided with a motor which drives the shaft 52 through suitable connections, not here illustrated. The shaft 52 extends longitudinally of the base 10 and passes through the gear housing or guard 38 of the frame unit 17. Within a portion of the gear housing 38 the shaft 52 is provided with a spiral gear pinion 53 which is splined to the shaft to rotate therewith and is adapted to mesh with a spiral gear 54 fixed to a shaft 55, the latter being rotatably supported in the housing 38. The shaft 55 has fixed to its inner end a gear 56 which meshes with the gear 37 and this gear in turn meshes with an idler

gear 57 supported on an adjustable bearing shaft 58 which can be adjusted and clamped in adjusted position by means of a screw or screws 59. This idler 57 drives a gear, similar to gear 37, on the next unit of the printing apparatus, as is fully described in my aforementioned copending application.

The cylinders such as 44 may take various forms, as, for example, they may be simply web-supporting cylinders formed of impervious sheet metal or they may be pervious to permit a liquid to pass therethrough for effecting a printing or coating operation. The tube 46 within the cylinder is adapted to have an electrode supported thereon for use as one element in an electrostatic printing couple, the electrical connections for which may extend through suitable openings within the tubes 46 and 47. When the cylinder 44 is to be used with a liquid contained therein, this liquid may likewise be supplied through the tubes 46 and 47 to facilitate such utilizations of the device. The tube 46 is therefore provided with a partition 60 which divides the tube into two separate compartments, one of which may contain the electrical connections for the electrode and the other of which may serve as a conduit for the liquid which is supplied therefrom to the openings in the surface of the cylinder in a manner described in my aforementioned application. The connections of the electrical and liquid conduits to the separate compartments within the tube 46 may be effected by disconnect couplings carried by the closed end of tube 46 and cooperating with conduits extending through the tube 47 as illustrated and described in my copending application to which reference is had for the details thereof.

Figs. 3 through 7 illustrate the present preferred embodiment of an apparatus constructed in accordance with this invention and which is similar in nature to the apparatus described with reference to Figs. 1 and 2. As shown in Fig. 3, the printing element or drum, generally designated 61, is designed for use in those forms of printing and coating where a liquid contained within the drum moves outwardly therefrom to effect or facilitate the printing or coating operation, this drum or cylinder being termed an "expulsion cylinder." For this purpose the element 61 is formed of a cylindrical outer surface or shell 62 which is pervious, being formed with suitable openings therethrough in any desired manner. The ends of the outer shell or cylinder 62 are removably supported upon circular shoulders 63 and 64 formed upon flanged disks 65 and 66, sealing means 67 and 68 being interposed between the outer shell and the circular shoulders upon the disks.

Interiorly of the outer shell 62, the element 61 is provided with a second or inner cylindrical shell 69 the ends of which are removably supported upon a circular shoulder 70, on the disk 66, and upon a circular shoulder 71, on an end plate 72, sealing means 73 and 74 being provided between the inner shell 69 and the circular shoulders on which it is supported. The end plate 72 is spaced inwardly from the disk 65 and is preferably provided with an integral circular boss 75 on the face thereof adjacent the disk 65 which circular boss is received in a corresponding circular recess in the disk 61 to locate the end plate 72 and the inner shell 69 thereby maintaining the latter concentric with the outer shell 62. The end plate 72 is connected with the disk 65 by screws 76.

The disk 66 is provided with an enlarged central opening in which is positioned a circular boss on a spindle 77, which spindle has a flange portion 78 engaging a portion of the outer face of the disk 66 and preferably secured thereto. The spindle 77 is rotatably journaled in a frame member 79, which may be similar to the frame member 17 in Fig. 1 or may be any suitable printing press frame structure. The rotatable mounting of the spindle 77 within the frame member is effected by means of spaced thrust bearings 80 and 81 of the conventional inclined tapered roller construction, the details of which need not be described. These bearings are spaced by a suitable spacing ring 82 and are retained from axial displacement by retaining members 83 and 84 connected with the frame member 79 on either side thereof as by means of screws 85 and 86.

The spindle member 77 has a shoulder 87 engaging the inner race of the bearing 81 while a flanged member 88 is interposed between the inner race of the bearing 80 and a collar member 89 connected by a screw or screws 90 to the outer end of the spindle member. Consequently, the spindle member is prevented from axial displacement relative to the press framework 79. Mounted upon the flanged member 88 and connected thereto by means of screws 81, or the like, is a driving gear 92 which may be connected with suitable rotating means, for example, similar to those shown for driving the gear 37 in Fig. 1, whereby the element 61 may be rotated.

The disk 65 at the left-hand end portion of the element 61 (as viewed in Fig. 3) has an integral boss 93 which is received in a cylindrical opening in the enlarged outer end of a spindle member 94. The spindle member 94 is rotatably journaled in a portion 95 of the press framework by means of tapered roller thrust bearings 96 and 97, the inner race of the bearing 96 engaging a shoulder on the spindle 94 while the inner race of the bearing 97 engages a flange member 98 which is connected to the outer end of the spindle member 94 by screws such as 99. Intermediate the outer races of the bearings 96 and 97 is provided a spacing ring 100 and the outer race for the bearing 96 is engaged by a retaining member 101 suitably secured to the adjacent end of a sleeve 102 in which the spindle and bearings are mounted. This sleeve has a shoulder engaging the outer race of the bearing 97 so that bearings 96, 97 and spindle 94 are held from relative axial displacement. The outer surface of the sleeve 102 is provided with an acme type screw-thread extending inwardly from the left-hand end thereof for a considerable distance upon which is threadably supported a nut member 103, the outer periphery of which is provided with gear teeth. The nut member 103 is prevented from axial displacement relative to the frame by means of a retaining plate 104 which is secured to the frame member 95 in spaced relation thereto, as by means of bushings 105 and bolts 106 (see Figs. 4 and 5).

The gear 103 meshes with a pinion 107 which is keyed or otherwise connected to a shaft 108 journaled in the frame member 95 and in a portion of the retaining plate 104. The outer end of the shaft 108 is provided with means, such as a polygonal surface 109, for receiving an operating handle or crank 110 by which the gear 107 may be turned, thereby rotating the nut 103 causing the latter to thread upon the sleeve 102 and move the latter and the spindle 94 axially. The sleeve 102 is held from rotation while permitting

axial movement thereof by means of a keyway 111 formed therein and in which is received the reduced inner end of a stud 112 secured in a stationary bearing boss of the frame member 95.

Liquid is supplied to the interior of the element 61 through a conduit 113 having a threaded connection with a nose member 114 which is secured to the outer end of the sleeve member 102 by means of screws or the like 115. The interior of the nose member 114 is provided with a sealing ring 116 which, in turn, carries a sealing ring 117 cooperating with the spindle member 94 to prevent the liquid from passing into the bearings 96 and 97. The spindle member 94 is provided with a central opening or passageway 94' therethrough aligned with the opening through the pipe 113 and with a central opening in the member 98. The inner end of this opening or passageway in the spindle 94 is enlarged to form a valve chamber in which a plug type valve 118 is supported. The valve member 118 has its outer end frusto-conical in shape for cooperation with a valve seat in a member 119 mounted within the cylindrical opening of the spindle 94, the valve 118 being normally urged to seating relationship by a compression spring 120. The opening through the member 119 is aligned with a valve seat opening in the boss portion of the disk 65 which communicates with a valve chamber in the said boss intermediate the end of this boss and the enlarged portion 75 of the plate 72. The last-mentioned chamber communicates with the opening between the plate 72 and disk 65 through suitable grooves or openings 75a in the portion 75, and the opening or space between plate 72 and disk 65 in turn communicates with the annular space between the inner and outer shells 69 and 62. Within the above-mentioned valve chamber provided in the boss 93 of disk 65 is a plug-type valve member 121 which has a frusto-conical portion cooperating with a correspondingly shaped valve seat portion, the valve being normally urged to seating position by a compression spring 122. A sealing means 123 is provided in the forward face of the boss 93 for cooperation with the member 119 to prevent leakage of liquid therebetween.

The valve construction just described is such that when the cylindrical printing element 61 is positioned within the printing press, as shown in the drawings, the valve 118 in the spindle abuts the valve 121 in the printing element and this abutting relationship causes both valve members to be unseated against the force of their respective springs 120, 122 to provide a passageway for a liquid theretofore and to the interior of the element 61 intermediate shells 62 and 69. When, however, the crank member 110 is rotated in a direction causing the nut member 103 to axially move the sleeve 102 and spindle 94 to the left, as viewed in Fig. 3, the abutting relationship of the valves 118 and 121 is terminated so that each valve is seated under the force of its respective spring 120, 122 thereby preventing loss of liquid from the passageway 94' through the spindle member and also loss of liquid from within the printing element 61 so that the latter may be readily removed and/or replaced without the spilling of liquid. The position of the parts when the spindle 94 is retracted to thus effect removal of the element and the corresponding closed position of the valves is shown in Figs. 6 and 7.

To facilitate support and axial alignment of the printing element 61 within the press, the

interior face of the inner plate 72 is provided with a cylindrical recess in which is positioned a ball bearing 124, the latter in turn receiving the reduced diameter portion of a cap member 125 positioned within a hollow tube 126. The tube 126 is preferably formed of insulating material and is adapted to support one electrode of an electrostatic couple for effecting a printing or coating operation by electrostatic means. The right-hand end of the tube 126 is received in, and connected to, the outer end of a stationary tube 127, the tubes being provided with an interlocking connection, such as the interengaging tongue and groove connection 128. The tube 127 is stationarily mounted in the machine by having a reduced end portion thereof received in an opening provided in a gear housing 129, the outer end of the tube being provided with a collar 130 which, together with an integral shoulder on the tube, cooperate with the housing 129 to hold the tube stationary and prevent axial displacement thereof. Adjacent the inner end of the tube 127 there is provided a thrust bearing 131, preferably of the tapered collar type, by which the tube 127 is supported within the spindle 77 in a manner permitting rotation of the latter relative to the former.

Let it be assumed that the apparatus is positioned as shown in Fig. 3 and that it is desired to remove the element 61 from the apparatus for cleaning and/or for replacement by another element. The operator rotates the crank 110 in a direction causing the nut 103 to move the sleeve 102 and the spindle 94 axially to the left, as viewed in the drawings, until these parts reach substantially the position shown in Fig. 6. From this figure, and the companion Fig. 7, it will be seen that the enlarged end of the spindle 94 is now spaced from the boss 93 of the disk 65 and the valves 118 and 121 are both closed. The disk 65, together with the attached end plate 72, and the inner and outer shells 69, 62 may then be moved axially with respect to the disk 66 until separated therefrom and at this time the tube 126 will likewise move axially with respect to the tube 127 separating at the tongue and groove connection therebetween. When the inner and outer shells and the tube 126 have thus been separated from the cooperating disk 66 and the tube 127, the element 61 may then be moved laterally from between the frame members 79 and 95 and, after removal, the shells 62, 69 and the tube 126 may be disassembled from the disk 65 and endplate 72 and the latter disconnected from the disk 65, if necessary or desired.

The same element or a different element may be reassembled in the apparatus by reverse operations. That is to say, the plate 72 is united with the disk 65 by the screws 76 and the inner and outer shells 69, 62 are mounted upon the circular shoulders 71 and 63 respectively. The tube 126 is then assembled with its cap member 125 and the outer end of the latter inserted in the bearing 124. The element 61 is then moved between the frame members 79, 95 and a rod or tool inserted through the hollow interiors of tubes 127 and 126 to effect alignment therebetween. This tool will preferably have a polygonal end portion interengageable with a polygonally shaped recess 125a in the inner face of the plug 125. The crank 110 is then rotated to operate as above described and move the spindle 94 inwardly toward the boss 93 of the disk 65 engaging the latter and thereby moving the shells 62 and 69 onto the cylindrical shoulders 64 and

70 of the disk 66. This likewise moves the tube 126 into the recess provided therefor in the outer end of the tube 127, the tube 126 being rotated, if necessary, by means of the tool engaged in the recess 125a, to effect interengagement of the tongue and groove connection 128 and of a positioning means for the shells similar to that shown in Fig. 2. The crank 110 may then be further rotated to clamp the shells 62 and 69 between the flanges of the end members or disks and thereby seat the boss 93 against the valve plate 119 with the two valve members 118 and 121 in abutting relationship and holding each other in open position as shown in Fig. 3.

15 As an alternative mode of disassembling and assembling the printing element shown in Fig. 3, this element can be caused to move with the spindle 94 when the latter is moved axially by operation of the crank. In such a case the disk 66 may be held stationary as before so that separation occurs first between the shells 62, 69 and the disk 66. Alternatively, the disk 66 may be free to move with the shells relative to the spindle member 77. In either case, the disk 65 20 may then be subsequently disengaged from the spindle 94 and the element removed from the press. Assembly of the element and positioning it in the press may be effected by reverse operations, circumferential positioning of the tube 126 25 being effected by a tool inserted through the tubes 126 and 127 and engaged in the recess 125a.

30 As mentioned above, the tube 126 is adapted to receive an electrode for effecting electrostatic printing, the electrical connections for which may 35 pass through the hollow interior of the tubes 126 and 127 and may be provided with readily disconnectible portions adjacent the outer end of the tube 127 or adjacent the inner end thereof, similar to that indicated in my above-mentioned 40 copending application.

45 It will now be apparent that, in accordance with this invention, there is provided an improved printing element and means for mounting the same by virtue of which the element may be readily assembled or removed from the printing press without dismantling the latter. Moreover, in the preferred form of the apparatus, a 50 means is provided for introducing liquid into the interior of the element intermediate an inner and outer shell thereof with the passageway for the liquid provided with cooperating valve means which automatically open when the element is in place in the press and automatically close when the element is being removed from the press, thereby preventing loss of liquid both from the 55 supply means and from the printing element. While specific constructional features have been illustrated and described in detail, it will be apparent that variations and alterations may be 60 made by those skilled in the art after having had the advantage of this disclosure and therefore the specific illustrations and descriptions are intended as representative only of practical embodiments of the invention and not as limitations 65 thereon.

Having thus described the invention, I claim:

1. In a printing press, a printing element comprising spaced flanged disks and a cylinder supported by said disks intermediate said flanges, 70 a supporting frame for said element including stationary bearing supports, supporting means including bearings carried in said frame providing a rotatable support for said element, a first tubular member stationarily mounted in said frame and extending axially into an opening in

one of said disks, a second tubular member located centrally of said cylinder, said tubular members having cooperating interlocking portions, said second tubular member being provided adjacent the end thereof removed from said first member with a polygonally shaped socket adapted to be engaged by a tool to thereby rock said second tubular member for effecting interengagement of the interlocking portions of both tubular members, and means carried by said frame and cooperating with one of said supporting means to effect axial movement thereof relative to said frame for selectively permitting removal from or support of said element and second tubular member in said frame.

2. In a printing press, a support, a drum carried by said support and including relatively movable flanged disks, a cylinder mounted on said disks and clamped in position by the flanges of said disks when the latter are in predetermined spaced relation, a stationary tubular member mounted axially in one of said disks, a second tubular member located centrally of said cylinder, said tubular members having cooperating interlocking portions, said second tubular member being provided at the end thereof remote from said first member with a tool receiving socket, a central opening in said other disk through which a tool may be inserted and engaged in said socket to rock said second tubular member for effecting interengagement of the interlocking portions of both tubular members, and means for relatively moving said disks from said predetermined spaced relationship to permit removal of said cylinder and said second tubular member.

3. In a printing press, a printing element comprising spaced flanged disks and a hollow pervious cylinder supported on said disks intermediate the flanges thereof, means within said element spaced inwardly of said cylinder providing an annular chamber adjacent the interior of said cylinder, one of said disks being provided with a centrally disposed axially extending passageway therethrough communicating with said annular chamber through which liquid may be introduced into said chamber, a supporting frame for said element, supporting means including bearings carried by said frame and normally engaging portions of said disks to provide a rotatable support for said element, means carried by said frame and cooperating with one of said supporting means to effect axial movement thereof relative to said frame and said element to selectively permit removal from or support of said element in said frame, the said one supporting means having an axially extending passageway therethrough adapted to communicate with the passageway in said element when the latter is supported in said frame, and cooperating valve means carried by said one supporting means and the adjacent one of said disks to close the said passageways when the element is removed from said frame.

4. In a printing press, a printing element comprising spaced flanged disks and a hollow pervious cylinder supported on said disks intermediate the flanges thereof, means within said element spaced inwardly of said cylinder providing an annular chamber adjacent the interior of said cylinder, one of said disks being provided with a centrally disposed axially extending passageway therethrough communicating with said annular chamber through which liquid may be introduced into said chamber, a supporting frame for said element, supporting means including bearings car-

ried by said frame and normally engaging portions of said disks to provide a rotatable support for said element, one of said supporting means having an axially extending passageway therethrough communicating with the passageway in said one disk when the element is supported in said frame, cooperating valve means in said communicating passageways continuously urged to closed position and positioned for interengagement to move the said valve means to open position when said one supporting means is in element supporting position, and means carried by said frame and cooperating with said one of the supporting means to effect axial movement thereof relative to said frame and said element to selectively permit removal from or support of said element in said frame.

5. In a printing press, a printing element comprising spaced flanged disks and a hollow pervious cylinder supported on said disks intermediate the flanges thereof, a flanged plate connected with the inner face of one of said disks in spaced relationship thereto, an impervious cylindrical shell extending coaxially of said hollow cylinder interiorly thereof and spaced therefrom with the ends of said shell supported upon said plate and upon a cylindrical shoulder on the inner face of the other of said disks thereby providing an annular chamber adjacent the interior of said cylinder, the said one of the disks being provided with a centrally disposed axially extending passageway therethrough communicating with said annular chamber through the space between said plate and the adjacent disk, a supporting frame for said element, supporting means including bearings carried by said frame and normally engaging portions of said disks to provide a rotatable support for said element, one of said element supporting means having an axially extending passageway therethrough communicating with the said passageway in said one disk when the element is supported in the said frame, means carried by said frame and cooperating with said one of the element supporting means to effect axial movement thereof relative to said frame for selectively permitting removal from or support of said element in said frame, separate valves in said passageways of said one disk and the said one supporting means respectively, the said valves being positioned to interengage and thereby hold each other in open position to provide communication through said passageways when the said supporting means are in element supporting position, and means acting on said valves urging them to closed positions to terminate such communication when said one supporting means is moved from supporting relationship with said element.

6. In a press of the type described, an element comprising spaced flanged disks and a cylinder supported on said disks intermediate the flanges thereof, a supporting frame for said element, supporting means including bearings carried by said frame providing a rotatable support for said element, means carried by said frame and cooperating with one of said supporting means to effect axial movement of the latter relative to said frame for selectively permitting removal from or support of said element in said frame, a first tubular member stationarily supported on said frame and extending through a central opening in the other of said supporting means and into a central opening in the adjacent disk of said element, a second tubular member dis-

posed centrally of said element with one end engaging the adjacent end of said first tubular member in interlocking relationship, and means rotatably supporting the other end of said second tubular member in said element adjacent that end thereof opposite the first tubular member.

7. In a printing press, a printing element in the form of a drum comprising axially spaced flanged disks and a cylinder supported by the said disks and clamped in position by the flanges of said disks when the latter are in predetermined spaced relationship, a support for said printing element, means carried by said support and cooperating with one of said disks for moving the said one disk axially relative to said support and the other of said disks to selectively permit removal of said cylinder laterally from said support or to position the said disks in said predetermined relationship and to clamp the said cylinder thereby, a tubular member extending centrally of said element, bearing means intermediate said element and tubular member permitting rotation of said element relative to said member, a second member stationarily mounted upon said support, and a readily disengageable connection between said first and second members whereby engagement of said connection facilitates proper positioning of the element in the said support.

8. In a printing press, a printing element in the form of a drum comprising axially spaced flanged disks, flanged plates supported on the adjacent flanged faces of said disks, and a hollow cylinder supported on said plates intermediate the flanges thereof so as to be clamped in position by the said disks when the flanges thereof are in predetermined spaced relationship, a support for said printing element, means carried by said support and cooperating with one of said disks for moving the latter axially relative to said support and the other of said disks for selectively permitting removal of the cylinder.

der and the plates as a unit laterally from between the disks or to position the said disks in said predetermined spaced relationship for clamping the cylinder and plates therebetween, 5 each of said disks and plates having a central opening therein, and a tubular member extending through the central openings of said plates and received in the openings of said disks thereby facilitating the removal of said plates, cylinder and tubular member as a unit from between the said disks or their insertion and clamping in operative position therebetween.

9. The combination as defined in claim 5 and further comprising an elongated member disposed centrally of said element and interengageable with a stationary member on said supporting frame thereby facilitating placing of said element in supported relationship in said frame, and means for permitting relative rotation between the element and said elongated member.

10. The combination as defined in claim 6 and wherein the said means for effecting axial movement of one of said supporting means includes an axially extending threaded portion on the latter, a threaded member rotatably supported upon said frame coaxially with said one supporting means and threadably engaged therewith, means for effecting rotation of said threaded member, and means preventing axial movement of said threaded member when rotated.

WILLIAM C. HUEBNER.
